UNITED STATES PATENT OFFICE.

FREDERICK H. CRAFTS, OF ROCHESTER, NEW YORK.

DESIGN FOR A TOOL FOR WORKING PLASTIC MATERIAL.

SPECIFICATION forming part of Design No. 24,892, dated November 12, 1895.

Application filed February 1, 1895. Serial No. 537,029. Term of patent 14 years.

To all whom it may concern:

Be it known that I, FREDERICK H. CRAFTS, of Rochester, in the county of Monroe, in the State of New York, have invented a new and useful Design for a Tool for Working Plastic Material, of which the following, taken in connection with the accompanying drawings, is a full, clear, and exact description.

Figures 1 and 2 are respectively top plan and side elevation of a tool for working plastic material embodying my design; and Fig. 3 is a vertical sectional view taken on line 3-3, Fig. 1, these views being deemed necessary to fully illustrate my design.

The leading feature of my design consists in an elongated body having concave and convex top and bottom faces arranged substantially concentric with each other, the top face being formed flat in cross-section, a handle projecting from one extremity of the body at an angle less than a right angle with a plane tangential with the top face of said extremity, and a substantially central longitudinal rib projecting downwardly from said bottom face and having its opposite side faces transversely inclined downwardly toward each other.

A is the longitudinal body of a tool embodying my design, and B C are respectively the handle and longitudinal rib projecting from its extremity a and bottom face a². The body A is of greater length than width, and its top and bottom faces a' a² are substantially flat transversely and are respectively concave and convex longitudinally. The faces a' a² are substantially concentric with each other, although their extremities a³ a⁴, adjacent to the handle B, curve outwardly from each other. The side and end faces a⁵ a⁶ of the body A are arranged at substantially right angles with each other, and the lower edges of the faces a⁵ are slightly rounded transversely. One of the end faces a⁶ is united to the adja-

cent extremities of the side faces a⁵ by rounding corners a⁷. The opposite extremities of the side faces incline or curve toward each other and the corresponding end face is of less width than the former face a⁶.

The handle B projects from one extremity of the body A at an angle less than a right angle with a plane B', Fig. 2, tangential with the top face of said extremity. The inner end b of the handle is formed cylindrical, its opposite end b' is rounding, and intermediate portions b² b³ thereof are formed, respectively, with concave and convex outer faces.

The longitudinal rib C is arranged substantially central with the lower face a² and projects downwardly therefrom. The lower edge of the rib C is arranged substantially concentric with the faces a' a² of the body A, and its extremity a⁵ curves toward the corresponding extremity of the face a². The side faces c² of the rib C are transversely inclined downwardly toward each other and are formed concave in cross-section at their upper edges.

A tool embodying my improved design has a pleasing and characteristic appearance and is used in the formation of cement and artificial-stone walks and in the manipulation of plastic materials.

What I claim is—

The design for a tool for working plastic material, substantially as shown and described.

In testimony whereof I have hereunto signed my name, in the presence of two attesting witnesses, at Syracuse, in the county of Onondaga, in the State of New York, this 28th day of December, 1884.

FREDERICK H. CRAFTS.
